UNITED STATES PATENT OFFICE.

ELROY N. HEATH, OF BOSTON, MASSACHUSETTS.

PACKAGE-CARRIER FOR VELOCIPEDES.

SPECIFICATION forming part of Letters Patent No. 479,069, dated July 19, 1892.

Application filed August 15, 1891. Serial No. 402,731. (No model.)

To all whom it may concern:

Be it known that I, ELROY N. HEATH, of Boston, county of Suffolk, State of Massachusetts, have invented an Improvement in Velocipede Package-Carriers, of which the following description, in connection with the accompanying drawings, is a specification, like letters on the drawings representing like parts.

Riders of velocipedes, bicycles, and the like frequently desire to carry bundles, packages, &c.

The object of this invention is to provide a package-carrier which may be easily carried and used, if desired.

15 My improved package-carrier resembles a hammock, and I have devised hammock-suspending devices by which it may be readily swung from the handle-bar or some other suitable part of the machine. I have shown the 20 suspending devices as clamps adapted to be clamped on the handle-bar, and preferably the part of the clamp next to the handle-bar will be covered or lined to prevent marring the handle-bar.

25 The whole contrivance may when detached be carried in the pocket of the rider.

My invention consists in the combination, with the handle-bar and hammock-supporting clamps and their bolts, of a hook and a hammock.

30 Figure 1 in elevation shows a sufficient portion of a velocipede or bicycle with my parcel-carrier attached to enable my invention to be understood. Fig. 2 is an enlarged view of the 35 suspending device and part of the handle-bar; Fig. 3, a like view with a hook of a different shape; Fig. 4, a like view showing the hammock-cord as applied directly to the suspending device without the intervention of a hook.

Fig. 5 is a section looking to the left of the 40 dotted line *x*, the hammock being omitted; and Fig. 6, a modification to be described.

Referring to the drawings, let A represent the pivot-post, and B the handle-bar, of any usual velocipede or bicycle.

45 In accordance with my invention as herein embodied I have applied to the handle-bar suspending devices C, made as clamps and adapted to surround and be clamped on the handle-bar by a bolt *a*, extended through ears 50 *c' c'* of the clamp. Preferably to avoid marring the handle-bar the clamp or suspending device will be lined or protected at the inner side next the bar with a split ring of non-metallic material, as india-rubber or leather, 55 as at *b*. The bolt *a* may serve to support a suitable hook *d*, to which the head cord *e* of the hammock *f* may be attached, as in Figs. 1 and 2. The hook may be made as a snap, as at *g*, Fig. 3, or the hook may be entirely dispensed with, the bolt *a* being extended through the looped end of the cord *e*, as in Fig. 4, or the bolt may be provided with a hook, as in the modification Fig. 6.

Having described my invention, what I 65 claim, and desire to secure by Letters Patent, is—

The bar B and the hammock-supporting clamps and their bolts, combined with a hook and a hammock, substantially as described. 70

In testimony whereof I have signed my name to this specification in the presence of two subscribing witnesses.

ELROY N. HEATH.
